ICE CREAM FREEZER

Leroy H. Knibb, Chicago, Ill.

Application May 7, 1957, Serial No. 46,053

Term of patent 14 years

(Cl. D67—2)

FIG. 1

FIG. 2

FIG. 3

FIG. 4

Fig. 1 is a perspective view of an ice cream freezer showing my new design;

Fig. 2 is a side elevation;

Fig. 3 is a bottom plan view; and

Fig. 4 is a rear elevation.

I claim:

The ornamental design for an ice cream freezer, substantially as shown.
